HERBERT PEARCE AND JOHN ERNEST BILLINGTON, OF BROADHEATH, ENGLAND,
ASSIGNORS TO LINOTYPE AND MACHINERY LIMITED, OF LONDON, ENGLAND.

COMPOSING MECHANISM OF TYPOGRAPHICAL MACHINES.

1,105,157.

Specification of Letters Patent.

Patented July 28, 1914.

Application filed October 30, 1911. Serial No. 657,436.

To all whom it may concern:

Be it known that we, HERBERT PEARCE and JOHN ERNEST BILLINGTON, subjects of the King of the United Kingdom of Great Britain and Ireland, and residing at Linotype and Machinery Works, Broadheath, in the county of Chester, England, have invented new and useful Improvements in the Composing Mechanism of Typographical Machines, of which the following is a specification.

The present invention relates to improvements in the composing mechanism of a typographical machine. Such a composing mechanism always consists of the three following elements or their respective equivalents:—(a) character finger keys arranged in the form known in the art as a keyboard; (b) organs generally arranged in a row to be actuated by the said finger keys, respectively, either directly or indirectly and (c) actuating means connecting each organ to its respective character finger key. It is a matter of indifference to the present invention, what is the exact type of the said organs. That may vary to any extent with the type of machine. For instance, they may be escapements controlling matrices as in the composing mechanism of the Mergenthaler line-casting machine, or punches punching holes in a mechanical controller as in the composing mechanism of machines known commercially under the trade mark "Monotype".

The application of the invention to the composing mechanism of a Mergenthaler line-casting machine has been chosen for specification. Such a machine is characterized by loose matrices stored according to their respective characters, A, a, B, b, 1, 2, et cetera, in channels in a magazine, from which channels they are liberated, one at a time, in the order of composition, by an escapement mechanism situated along the delivery mouth of the magazine and which is worked from a keyboard similar to that of a type-writer. As the matrices escape from the magazine, they are assembled in a composed line which corresponds exactly with the intended line of print. The composed line of matrices is then presented by the machine to its casting mechanism which proceeds to cast a bar of type metal as long as the intended line of print and having in re-

lief on one of its long edges, the characters 55 properly spaced out into words to print that intended line. As soon as this bar has been cast, the composed line of matrices is distributed, each of its matrices being returned by the machine to the particular channel 60 from which it was liberated, but into the end of it opposite to that from which it was liberated. Such a machine has been made capable of carrying two fonts of matrices differing from each other in style of character 65 or "face" (to use the technical term) by adding a second magazine equipped with the additional font, the two magazines being parallel with each other and one above the other. Obviously, the operator could not 70 ever be called upon to compose from both magazines, i.e., in both faces, at one and the same moment of time, although it is just possible that he might be called upon to change "face" immediately after he had 75 liberated only one matrix in the preceding face, so that the addition of the second magazine did not necessitate the addition of a second keyboard provided that a switch was introduced between the keyboard on the one 80 hand and the two sets of matrix escapements (one set on each magazine) on the other.

Taking the number of characters in a font, including spaces and punctuation marks, as 85 90 (there might be more or less than this—it is only an assumed number), there would be 90 finger keys on the keyboard. These finger keys would coöperate with as many matrix escapements of either magazine, according to which set of escapements the switch had switched them on to.

Referring to the accompanying drawings: Figure 1 is a right-hand side elevation of a portion of a Mergenthaler composing mechanism, having two superposed magazines and a manually operable switch, and illustrating the keyboard mechanism, etc.; Figs. 2 and 3 are together a similar right-hand side elevation thereof, having our invention 95 applied thereto; Fig. 4 is a detail front elevation of a portion of the same; and Figs. 5 to 10 are detached detail views.

Referring to Fig. 1, 1, 1 are two of the matrices in their respective channel 2, 2 of the 105 magazine 3; and 4, 4, two of the matrices in their respective channel 5, 5, of the magazine 6, all the matrices in each channel having

the same character. One magazine, say 3, is equipped with matrices having one style of character, say thick lined, while the other magazine 6 is equipped with matrices having another style, say thin lined. Further, each matrix has its own character in duplicate, say roman and italic. There would be the same number of channels in each magazine as there are characters in a font, but although the two magazines 3, 6, are equipped with two styles of character, each style in duplicate, making in all four varieties of character, the machine would have a font of only (say) 90 characters, because although the operator has a choice of four varieties of character, this choice of variety leaves the inclusiveness of the font limited to that number of characters. Both magazines are flat, the channels in each standing behind each other, looking at Fig. 1. They are oblique in order that the matrices may slide along the respective channels by gravity. Each channel 2, 2, of magazine 3, has its own escapement lever 7 fulcrumed at 8 on the magazine. 9 is a spring making a lever 7 hold a pawl 10 in engagement with the leading matrix 1, *i. e.*, the one nearest the delivery mouth 11 of the magazine. A pawl 10 is held in that position by an escapement rod 12 pulled down by a spring 13. If the rod 12 were pushed up, it would withdraw the respective pawl 10 out of engagement with the said leading matrix 1, thereby liberating it, whereupon it would drop through the mouth 11 on its way to the assembling mechanism. The withdrawal of the pawl 10 would be accompanied by the engagement of the pawl 14 with the next matrix 1. When the spring 13 is allowed to pull the rod 12 down again, the said next matrix 1 would slide down a short distance only, however, to be engaged by the pawl 10. So that a reciprocation of a rod 12 means the liberation of the leading matrix 1 from the respective channel 2, 2. Each channel 5, 5, of the magazine 6, has likewise its own escapement lever 16 fulcrumed at 17 on the magazine, its spring 18, its pawls 19, 20, and a link 21 from a lever 16 to the respective escapement rod 22 which is pulled down by a spring 23. A rod 22 stands edge on exactly opposite a rod 12. The two magazines, 3, 6, have not ordinarily, a font divided between them and only one magazine can be composed from at a time. Consequently, although each of the matrix channels 2, 2; 5, 5; in the magazines 3, 6, has its own escapement lever 7 or 16 and its own escapement rod 12 or 22, there are only half that number of finger keys 24 on the keyboard. Each finger key 24 is fulcrumed at 25 and has its inner end loosely engaged with a vertically sliding bar 26 whose top end is loosely engaged with the horizontal arm of a bent lever 27 turning on a fixed fulcrum 28 and

supporting by its upstanding arm, the free end of a lever 29 turning on a fixed fulcrum 30. A lever 29 has a cam 31 rotatable in a slot 32 therein about a pivot 33. There is a set of parts 27 to 33 inclusive for each bar 26, and as these bars 26 are thin and must be close together, room for the said sets of parts is found by placing one half of them in front of the row of bars 26 and the other half behind it. 34 is a roller extending under each half set of cams 31 at a short distance below it, both rollers being kept constantly rotating by the machine. 35 is a vertically sliding bar resting by its bottom end upon one of the inner ends of two levers 29 that are opposite each other, and holding its top end under, but at a short distance below, the plane of the bottom end of the respective escapement rod 12 or 22. There is a bar 35 for each pair of rods 12, 22. The bottom ends of both rows of escapement rods 12 and 22, are embraced by a loop 36 connected to a bell-crank lever 37 turnable by the operator on a fixed fulcrum 38, far enough in either direction to move the bottom ends of one row of escapement rods 12 or 22 away from over or into position over the row of rods 35. The depression of a finger key 24 raises the respective bar 26 thereby making it raise the respective lever 29 far enough to place its upstanding arm under the respective slot 32 in the respective lever 29, whereupon the latter drops until its cam 31 rests upon the respective roller 34. The respective cam 31 is then rotated once, 100 its longer radius rocking the free end of the respective lever 29 upward and making it raise the respective escapement rod 12 or 22 as the case may be. At the moment when a cam 31 completes its single revolution, its bent lever 27 engages under the inner end of its lever 29 thereby holding it off the roller 34 and its cam is automatically stopped. Thus the combination of parts 27 to 33 with the respective roller 34 constitutes a power-driven mechanical relay capable of working the escapement mechanisms, the superior strength of such relay (because it is power-driven) allowing of each depression of a finger key 24 being affected by only a light 115 touch on the part of the operator, while the combination of the row of bars 35, loop 36, and lever 37 is a manual shift between the keyboard on the one hand and either of the two alphabets of matrices in the respective magazines 3 or 6, on the other. 120

Now it must be clearly understood that all the character finger keys 24 of the composing mechanism described in connection with Fig. 1 require the same degree of pressure 125 on the part of the operator to effectively depress them. This degree of pressure is only a small one and is known to operators as a "light touch". Now the switch lever 37 of Fig. 1, requires considerably more power 130

than this "light touch" to work it, and the like is true of every switch lever which it has been proposed to combine with the keyboard of a composing mechanism of a typographical machine.

5 The present invention consists mainly in the combination with a keyboard of "light touch" finger keys, of an equally "light touch" finger key to work the shift. It comprises other and dependent improvements. 10 The said combination and dependent improvements are hereinafter specified at length.

15 Referring now to the other figures of the drawing 61 (Fig. 3) is one of the set of shift bars. This set is functionally identical with the set of bars 35 of Fig. 1.

20 126 is the "light touch" finger key to work the shift. There is interposed between the shift finger key 126 and the shift, a mechanical relay which is put into action by the depression of the said key 126. The preferred construction of this relay is as follows. One of the rollers 34, preferably the 25 front one, has a stud 102 (Fig. 4) alined with it and detachably connected with it by a tooth and slot arrangement 103. The stud 102 is fast to a gear 104 meshing with a gear 105 turning on a fixed stud axle 106 (Fig. 3). 30 107 is a mutilated gear meshing with gear 105; 108, a cam; and 109, a disk, the three integral with each other and turnable together on a fixed stud axle 110.

111 is an arm fast on a transverse shaft 35 112 turning in bearings on the machine frame; and 113, one or more upstanding arms on the said shaft. The arms 113 are connected with the row of shift bars 61 by any suitable means. Fig. 3 shows a means 40 consisting of a loop 114 carried by the top ends of the arms 113 and embracing the row of bars 61. The reciprocating motions of the loop 114 are guided by rollers 115 on fixed axes above and below it. The front end of 45 the arm 111 is kept in constant contact with the periphery of the cam 108 by a spring 116 pulling on it from a fixed point 117 on the machine frame.

118 (Fig. 4) is a clutching pin free to slide 50 in a hole in the disk 109, the axis of the hole 119 being parallel with the axis of the disk and coincident with the intersection of a circle thereon of the same diameter as the pitch-circle of the gear 107, by a diameter of 55 the said disk, and which intersection is intermediate of the two arcs of gear teeth (Fig. 6) on the mutilated gear 107. There is a similar pin on the opposite side of the axis of the disk 109. The motion of each pin 60 118, 118, away from the gear 107, is limited by a shoulder 120 on the respective pin and the bottom of the respective hole 119 or by a plate 121, fast to the disk 109.

122 (Figs. 3 and 10) is an arm fast on the 65 gear 105 and rotating between the disk 109

and the gear 107. The contour of its leading face is an involute curve with respect to its axis.

123 is a cam piece stationary between (Fig. 4) the disk 109 and the gear 107.

124 is a bell-crank lever fulcrumed at 70 125 on the machine frame and holding its free end opposite a pin 118. Its opposite end is connected to a special finger key 126 fulcrumed at 127 on the keyboard, by a link 128 and a lever 129 intermediate of the said finger key 126 and link 128, pivotally connected to both by its respective end, and fulcrumed at 130. The periphery of the cam 108 has a depression 131 in it on its long 80 radius and a similar depression 132 on the short one. There is, or may be, combined with this mechanical relay, an indicator to show the operator which set of escapements the shift stands set, at any given moment, to 85 coöperate with. A suitable one is shown in Figs. 3 and 4.

133, 134, are two tablets inside a frame 135 fast on the front of the machine, the tablet 133 bearing the word "Upper" and 90 the tablet 134, the word "Lower", these two words referring to the respective positions of the two divisional magazines 41, 40.

136 is a plate having a slot in it large enough to show one tablet 133 or 134 to the operator while it conceals the other one from him. This plate 136 is caused to slide vertically in both directions in the frame 135 and in front of the tablets 133, 134, by the rocking of the arm 113 acting through a lever 137 and a link 138, the lever 137 being alined with the arm 111, centrally fulcrumed in front of it on a fixed fulcrum 139, and having its opposite ends pivotally connected to the said arm and link respectively 105 by the pivots 140, 141.

The mechanical relay and indicator just described, act as follows. So long as the shift does not require to be actuated, the spring 116 holds the front end of the arm 111 in one of the depressions 131, 132; the plates 119 intermediate of the two arcs of gearing on the mutilated gear 107; and the pin 118 that is nearest to the arm 122 within reach of the lever 124. The roller 34 is 115 keeping the arm 122 revolving past the hole 119 next to it. The figures show the shift set to coöperate with the set of escapements on the lower divisional magazine 41. Consequently, the cam 108 holds the sight- 120 ing slot in the plate 136, opposite the tablet 134 which is marked "Lower." When the operator wants to compose from the divisional magazine 41, he depresses the finger key 126, thereby pushing the pin 118 then 125 opposite the lever 124 into the path of the arm 122. The latter then engages the said pin 118, thereby rotating the gear 107, cam 108 and disk 109 far enough to put the gear 107 in engagement with the gear 105 which 130

thereupon turns it, the disk 109, and the cam 108. As they are being so turned, the said pin 118 rides up the cam 123 which returns it into the disk 109 at the moment the 5 arc of gearing on the mutilated gear 107, which had been engaged by the gear 105, had passed the latter, whereby it, the disk 109, and the cam 108, cease to turn. At the same moment, the depression 132 comes 10 under the front end of the arm 111, whereupon the spring 116 pulls the sighting slot in the plate 136 opposite the tablet 133 marked "Upper" and makes the plate 136 cover the tablet 134. Whenever the operator 15 wants the shift mechanism to act, all he has to do is to depress the finger key 126 with a normal touch, and the automatic mechanical relay does the rest.

The character finger keys of the keyboard 20 of the invention, are not included in the figures devoted to the illustration of it, viz:—Figs. 2 to 10, because they are of the well known construction and are "light touch" keys. This keyboard has as many 25 character finger keys as either magazine 40 or 41 has magazine channels 43 for the matrices 44 or magazine channels 43^a for the matrices 44^a. The two magazines 40, 41 may be either superposed as shown in Fig. 2 or 30 side by side in the same plane. Each may be equipped with its own font complete in itself or with any other arrangement of characters desired. The number of characters 45, 46, on each matrix is dealt with 35 farther on. The combination of escapement levers, springs, pawls, escapement rods, bent levers 27, levers 29, cams 31 and rollers 34, is the same as that described with reference to Fig. 1; and the several parts of it are 40 therefore marked with the same reference numbers. In the mechanism illustrated it is the escapement levers 7, 16, that are the above mentioned "organs to be actuated by the character finger keys;" and the rods 12, 45 22, and bars 26, 61, that are the above mentioned "actuating means connecting each organ to its respective character finger key."

As the matrices issue from their respective 50 divisional magazine 40 or 41 (Fig. 2), they pass through respective channels 90, 91, 92, into the part of the machine known as the assembler. This part is well known in the art, and consequently, forms no part of the 55 present invention. The matrices issuing in the order of composition from the bottom ends of the channels 92, are assembled, side by side, in the assembler.

The above mentioned continuous font may 60 be doubled by placing two characters on each matrix, the two differing from each other to any extent. Such a doubling is shown in Fig. 2 where each matrix has two such characters 45, 46. All the matrices whose characters 46 are to be in the composed line, 65 stand at one level in the assembler, while

those whose characters 45 are to be in that line, are automatically raised as they enter the assembler, to make them present their characters 45 in that line, and are automatically supported in that raised position. The 70 devices for so raising and supporting are likewise well known in the art, and consequently, form no part of the present invention.

The terms "matrix," "matrices," are to be 75 understood throughout this specification as including "type die," "type dies," respectively.

Having described our invention, we declare that what we claim and desire to secure 80 by Letters Patent is:—

1. In composing mechanism for a typographical machine, the combination with a keyboard, a plurality of series of organs actuated thereby, and a power driven shift 85 to connect the key board with any selected series of organs, of a finger key adapted to control the said shift.

2. In composing mechanism for a typographical composing machine, the combination with a keyboard, a plurality of series of organs actuated thereby, and a shift to connect the key board with any selected series of organs, of a finger key adapted to work 90 the said shift and a power driven relay 95 through which the said finger key controls the said shift.

3. In composing mechanism for a typographical composing machine, the combination of keyboard, a plurality of series of organs actuated thereby, a power driven shift 100 to connect the key board with any selected series of organs, and a finger key adapted to work the said shift, the said keyboard comprising half as many character finger keys 105 as there are organs to be actuated by them.

4. In a typographical machine, the combination of a plurality of magazines each provided with a series of escapements, a corresponding plurality of series of actuating 110 devices for the escapements, a keyboard mechanism, a power driven shift to connect the keyboard mechanism with any selected series of actuating devices, and a finger key adapted to control the said shift.

5. In a typographical machine, the combination of a plurality of magazines each provided with a series of escapements, a corresponding plurality of series of actuating devices for the escapements, a single series of 115 operating members, a power driven shift to connect said members with any selected series of actuating devices, and a finger key adapted to control said shift.

6. In the composing mechanism for a 125 typographical composing machine, a mechanical relay comprising a constantly rotating gear carrying an arm; a rotatable set of clutching pins one of which is to be put in the path of the said arm by a finger key; 130

the said finger key; the cam and set of arcs of gearing fast to the set of clutching pins and rotatable through one arc by the first mentioned gear; operative connection between the said cam and the shift of the composing mechanism; and automatic means for disengaging the acting clutching pin as soon as the said shift has been reset.

7. In a typographical machine comprising 10 composing mechanism, the combination of a plurality of series of escapement devices, and a single series of actuating means therefor, with power operated shifting mechanism to bring the series of actuating means into operative relation with any selected series of 15 escapement devices as desired, and means to control the operation of said shifting mechanism, at will.

8. In a typographical machine comprising composing mechanism, the combination of a 20 plurality of series of escapement devices, and a single series of actuating means therefor, with power operated shifting mechanism to bring the series of actuating means into operative relation with any selected series of 25 escapement devices as desired, and a finger key and connections to control the operation of said shifting mechanism.

In witness whereof we have hereunto set our hands in the presence of two witnesses. 30
